DAVID LARSON, OF YONKERS, NEW YORK.

ALTERNATING-CURRENT CONTROLLER.

No. 833,968.

Specification of Letters Patent.

Patented Oct. 23, 1906.

Application filed September 28, 1905, Serial No. 280,424.

To all whom it may concern:

Be it known that I, DAVID LARSON, a subject of the King of Sweden, and a resident of the city of Yonkers, in the county of Westchester and State of New York, have invented certain new and useful Improvements in Alternating-Current Controllers, of which the following is a specification.

My invention relates to electrical controllers for use in conjunction with alternating, intermittent, or pulsating currents; and it consists in the construction and arrangement of parts herein shown and described, the novel features whereof are pointed out in claims.

Referring to the drawings, Figure 1 is a diagrammatic view of an electric motor and other apparatus and various electrical connections, which taken together illustrate my invention. Fig. 2 is a similar view showing a modification of the invention. Fig. 3 is another modification showing the invention as applied to single-phase circuits.

Like characters of reference designate corresponding parts in all of the figures.

10 designates an alternating-current motor. 20, 21, and 22 designate mains from a suitable source of electrical supply which may pass through a transformer 23, fuses 24, and 30 a manually-operated main switch 25 and thence by conductors 26 27 28 to other apparatus, which will be described hereinafter.

35 30 40 designate the magnets of an electrically-actuated reversing-switch S for starting the motor in either direction. The magnet 30 comprises a frame 31, preferably of laminated magnetic material, a core 32 or armature of similar material, an exciting-coil 33, three stationary contacts 34 35 36, 40 and three movable contacts 37 38 39, which are mounted upon but insulated from a cross-bar 32^A, which is connected to the core 32 by a rod 32^B. The magnet 40 comprises similar parts.

45 50 is a manually-operated master-switch, which may be in any convenient location. It comprises a pivoted lever 51, which carries two contact-plates, the lower of which is adapted to connect a stationary segmental contact 52 with either stationary contact 53 or a similar contact 54, while the upper of which is adapted to connect a stationary segmental contact 55 with any one of a series of

stationary contacts 56, which are connected together through resistances 57.

55 Before proceeding with the description of the rest of the apparatus I will trace the connecting-circuits and describe the operation of the parts above described.

The contact 52 is connected to the main conductor 27 by conductor 27^A. When an operator moves the pivoted lever 51 of switch 50 to the left, a circuit is closed thereby between contacts 52 and 53 and a current will flow from main 27, conductor 27^A, contacts 52 and 53, which are now bridged by pivoted arm 51, conductor 53^A, magnet-winding 33, and conductor 28^A to main line conductor 28. Magnet 30 will be energized thereby and will raise its core 32 and its connected 70 parts, so that movable contacts 37, 38, and 39 will be closed against stationary contacts 34, 35, and 36, respectively. Main line conductor 26 is connected to contact 39, and as this is now in contact with contact 36 and as 75 the latter is connected by conductor 11^A to motor-terminal 11, main line 26 will thus be connected to one of the motor-terminals 11.

Main line conductor 28 is now similarly connected, through contacts 37 and 34 and conductor 13^A, to motor-terminal 13. At the same time main line conductor 27 is connected, through contacts 38 and 35, to conductor 12^B, and the circuit continues through this conductor 12^B to and through coils 63 85 and 64 of an electromagnetic actuating device 60, which will be described later, and through conductor 12^A to the central motor-terminals 12. In this manner the motor may be connected to the source of supply and 90 will begin to rotate in one direction. When pivoted lever 51 is moved back to central position, the circuit through magnet-winding 33 will be broken and magnet 30 will be de-energized. It will then allow its core and its 95 connected movable contacts to drop, the current-supply will be cut off from the motor, and the latter will come to rest. If the operator had moved pivoted lever 51 to the right, the operation would have been similar; 100 but in this case the magnet 40 would have been energized and would have closed main 28 to motor-terminal 11 through contacts 49 and 46, main 27 to motor-terminals 12 through contacts 48 and 45, and main 26 to 105 motor-terminal 13 through contacts 47 and

44. This would supply current to the motor in the opposite direction and would cause it to rotate in the opposite direction.

An opposition element may be included in the motor-circuit to prevent its rotation from being too fast. 80 designates a star-connected resistance which is connected in series with the rotor-circuit of motor 10 for this purpose. Its outer ends are connected by conductors 14^a, 15^a, and 16^a to brushes 14, 15, and 16, which are connected to the rotor-windings through rings in a well-known manner. It is desirable to gradually cut this opposition element out of the motor-circuit as the motor accelerates and to thus control its acceleration. It is also desirable that this should be done with greater or less rapidity, according to the load upon the motor, which may be a variable quantity. I will now describe an arrangement which I have invented for accomplishing these ends and for automatically controlling the acceleration of the motor.

60 and 70 designate electromagnetic actuating devices. 60 comprises a magnetic frame 61, preferably of laminated magnetic material, and a rotatable armature 62, which is attached to a shaft 65 and which is arranged to swing between two pole-pieces 61^a and 61^b, which are a part of the magnetic frame 61. Rigidly mounted upon shaft 65 and arranged to move in unison with armature 62 is a toothed segment 65. The armature or rotatable member 62 is shown in the drawings in a horizontal position and situated in such a manner as to include a maximum number of magnetic lines of force which pass between pole-pieces 61^a and 61^b when they are energized. It has been shown that all the current passing from main conductor 27 to the motor 10 passes through the windings 63 64, and these are placed upon the pole-pieces 61^b and 61^a. The motor-current then will energize these pole-pieces, and this will tend to hold armature 62 in the position in which it is shown. It is also evident that this energization will be proportional in strength to the total motor-current. 70 designates a similar electromagnetic actuating device. Its magnetic frame 71, with its pole-pieces, is arranged to be energized by a current passing through its coils 73 and 74. When either side of the reversing-switch S is closed, the main line conductor 27 will be connected, as has been shown, through contacts 38 35 or through contacts 48 45 to conductor 12^b. Another conductor 12^b is attached to 12^b and runs to the coil or winding 73. The other end of winding 73 is connected to winding 74, and the other end of 74 is connected by conductor 74^a to the two outer stationary contacts 56 on the master-switch 50. The stationary segmental contact 55 is connected by conductor 11^b to conductor 11^a, which we have seen is connected, through

contacts 39 36, to the main line conductor 26 or through contacts 49 and 46 to main line conductor 28 whenever one side or the other of the reversing-switches S is closed. It is evident then that whenever pivoted lever 51 is moved to its extreme position to the left or right position the coils 73 and 74 will be connected directly across mains 27 and 26 or 27 and 28 and in shunt with the motor. Consequently the magnetic frame 71 will be energized in proportion to the voltage in the mains. The armature 72 is held normally in the position in which it is shown in the drawings. When the pole-pieces 71^a 71^b are energized, the armature 72 and its connected toothed segment 75 will be pulled thereby in an anticlockwise direction, as the armature will tend to move into such a position as to include the maximum number of magnetic lines. This pull will be approximately proportional to the voltage in the main line. It may be seen that each of these actuators has a tendency to pull its rotatable member into a state of magnetic equilibrium in such a position as to include the maximum number of magnetic lines of force and that the actuators cannot move these members beyond such position.

90 designates an arm which is pivoted at 91 and which is geared to toothed segments 65 and 75 by other toothed segments 92 92'. An adjustable weight 90' at one end of this arm tends to keep the parts normally in the positions in which they are shown in the drawings. The arm 90 is connected by a link 93 to a sliding frame 94, in Fig. 1, to the upper end of which is attached a core 95, which is arranged to be moved out of and into a choking-coil 96. Mounted upon the top of the frame 94, but insulated from it, is a contact-plate 97, above which are placed three stationary contacts 97^a, 97^b, and 97^c, which are connected to the outer terminals of resistance 80 and to brushes 14, 15, and 16 on the motor 10. Upon one side of frame 94 is placed a block of insulating material 98^a which carries a contact-strip 98. A stationary brush 99 bears upon this contact-strip when the parts are in the position shown.

1, 2, and 3 designate three electromagnets. The magnet 1 comprises a frame 1^a, a core 1^b, and a winding 1^c. It also has in conjunction with it three stationary contacts 1^d, 1^e, and 1^f, which are connected, respectively, to points 81, 82, and 83 on resistance 80. A contact-plate 1^g is arranged to be lifted by magnet 1 against these stationary contacts when the magnet is sufficiently energized and to thereby short-circuit that portion of resistance 80 which is included between the points 81, 82, and 83. Magnets 2 and 3 have similar parts to those just described and are similarly connected to resistance 80.

A conductor 12^c is connected to the left-hand sides of the three magnet-windings 1^c,

2°, and 3° and to the conductor 12°, which, we have seen, is connected to the main 27 whenever the reversing-switch S is closed. The other ends of these magnet-windings are 5 connected together and by conductor 96^A to choking-coil 96, and a circuit is then completed through coil 96, conductor 96^B, contact-strip 98, brush 99, conductor 99^A, to conductor 13^A, which is connected to main 10 28 or main 26 when one side or the other of the reversing-switch S is closed. Thus the windings of the magnets 1, 2, and 3 are connected when the reversing-switch is closed in parallel across two of the mains through the 15 choking-coil 96. These magnets may be arranged to be actuated one by one as the current supply to them increases. This may be accomplished in a number of ways—as, for example, by having a different number of 20 turns in each winding. As shown, winding 1° has the greatest number of turns, winding 2° has a smaller number, and winding 3° has the smallest number of turns. Consequently when a current of increasing strength is supplied to these magnets they will be energized 25 sufficiently to lift their cores in succession.

I will now describe the operation of the electromagnetic actuating devices and the parts which they control.

30 When the operator moves pivoted lever 51 of master-switch 50 way over to the left or right, and thereby starts the motor in one direction or the other, the actuating devices will both be energized, as we have seen. Actuating device 70, which is energized in proportion to the amount of voltage in the main lines, will through its connected parts tend to lift the weighted end of arm 90 and the sliding frame 94. The tendency of actuating 35 device 60 is to prevent such movement, and the parts may be so proportioned and adjusted that the arm 90 will not be moved so long as the motor-current which energizes the actuating device 60 is of a certain predetermined strength. As the motor accelerates this current will decrease, and consequently the retarding and holding effect of actuating device 60 will decrease and will allow actuating device 70 to raise arm 90 and 40 sliding frame 94. This will raise core 95 out of choking-coil 96. This coil is preferably placed within a frame 96', of laminated magnetic material, and is itself constructed of laminated magnetic material, and the impedance of coil 96 is sufficiently high to prevent 45 enough current to pass through it to cause magnets 1, 2, or 3 to lift their cores. Now when core 95 is raised a certain amount this decreases the impedance of coil 96 and allows 50 more current to pass through it and through magnets 1, 2, and 3. When core 95 is raised far enough to allow enough current to pass to energize magnet 1 sufficiently for it to raise its core, it will do so and will bring contact-plate 1° up against stationary contacts 55

1°, 1°, and 1°, and will thus short-circuit that portion of resistance 80 which lies between the points 81, 82, and 83. This will allow the motor to take more current, which will of course increase its acceleration and at 60 the same time increase the holding or retarding effect of actuating device 60 and prevent a further movement of core 95 until the motor-current has again decreased. Then actuating device 70 will raise core 95 farther 65 until it allows enough current to pass to cause magnet 2 to raise its core 2°, and thus short-circuit another portion of resistance 80. Similarly, magnet 3 will be actuated and short-circuit a further portion of resistance 80. 70 Finally, actuating device 70 will raise core 95 to its extreme upper position, when contact-plate 97 will be brought against stationary contacts 97^A, 97^B, and 97^C and will thereby short-circuit all of resistance 80. This will 75 allow motor 10 to take full power from the line and to attain maximum speed. At the same time sliding frame 94 will be raised up to such a position as to cause the stationary brush 99 to run off of contact-strip 98 and 80 onto insulating-block 98^A. This will cut off the current from magnets 1, 2, and 3 and prevent unnecessary current consumption by them after they have performed their function. Then the current is cut off from 85 the motor and from the electromagnetic actuating devices. Weight 90' will immediately bring the arm 90 and its connected parts back to their initial position.

The operation above described is automatic. Means may be provided, however, for giving an operator partial control of the operation. For this purpose I have provided the resistances 57, which are connected to the stationary contacts 56. It is obvious that the operator may include more or less of this resistance in circuit with coils 73 and 74 by moving pivoted lever 51 onto one or another of stationary contacts 56. Thus he may retard the action of actuating device 70 90 and the acceleration of the motor; but he cannot increase its action and thus cause the motor to accelerate too rapidly.

It is sometimes desirable to further govern the movement of arm 90, and for this purpose 95 a mechanical retarding device 100 may be provided. A third toothed segment 92^A is shown on one end of arm 90, and this is in mesh with a pinion 101, which is attached to a ratchet-wheel 102. A gear-wheel 103 carries a pawl 104 and meshes with the pinion 105, upon the shaft of which are mounted two fan-blades 106. These may be so arranged that they may be moved in or out from the shaft, so that their retarding effect may be 100 adjusted. When arm 90 is moved to raise its weighted end, the mechanism just described will drive fan-blades 106, and these will retard the movement of arm 90 in that direction. The ratchet-and-pawl arrange- 105

ment will, however, allow arm 90 to drop freely without driving fan-blades 106, and thus without their retarding effect.

In Fig. 2 I have shown certain modifications of details in an electrical controller system similar to that already described. The resistance 80' is shown delta-connected. The exciting-coils 63 and 64 of electromagnetic actuating device 60 instead of being connected in series and in the central main line conductor 27 are shown separate, with coils 63 and 64 connected in series with the outside main line conductors 26 and 28. Pivoted arm 90 is connected by link 93 to a sliding member 94', which in this case is a cam member which controls the movement of a series of pivoted arms 120 and allows them to make contact with or moves them away from a corresponding series of stationary contacts 121. These pivoted arms and stationary contacts may be connected to resistance 80' and may be arranged to short-circuit the latter directly without the intervention of electromagnets when the arm 90, with its connected parts, is raised.

Fig. 3 illustrates another modification of my invention and shows that it is applicable to single-phase circuits. The motor 10' is here shown as a series-connected single-phase motor. The main line conductors 20' 22' are shown connected to the primary of a regulating - transformer 130. Several points of the secondary of this regulating-transformer are connected to stationary contacts 131, one or another of which may be connected to a contact-strip 132 by a sliding contact 133, mounted upon a sliding rod 134. Contact-strip 132 is connected to the motor 10' through reversing-switch. Sliding contact 133 may be arranged to be moved by the arm 90 and to include more and more of the secondary of regulating-transformer 130 in the motor-circuit and to thus supply the motor with an increasing voltage as it accelerates, which voltage may be controlled and regulated by means of the apparatus and devices previously described in this specification.

When this invention is applied to a motor-starting device, the acceleration of the motor will depend upon the total amount of motor-current, upon the voltage of the line, upon the effect of the mechanical retarding device, and upon the position of the master-switch 50. The actuator 60 has a retarding effect upon the actuator 70 and their connected parts, as well as a holding effect. It may, in fact, if the motor-current becomes excessive push arm 90 down; and thus cause a reduction of the motor-current.

As the various magnet-winding actuator-coils may be connected across two of the mains, as described, it is evident that they may be arranged to be actuated by single-phase currents.

One of the disadvantages usually experienced in alternating-current apparatus is the noise produced by the pulsations of the current. My actuators overcome this trouble, for the rotating members swing freely between their respective pole-pieces and do not touch them. The two rotating members tend to balance themselves between their respective pole-pieces and of course must act in unison, actuated by the differential action of the current in each. Moreover, the two rotating members are mechanically connected together, and as they exert pulls in opposite directions upon the gears the latter will not chatter.

This invention is applicable to many other uses than those herein shown and described. I have shown it as applied to a motor-starting system, as this is one of its advantageous uses.

The controlled motor may be connected to run elevators, cranes, mill-tables, or railroad-cars or to any similar use where it is desirable to have a steadily-increasing current supplied to the motor and a current which cannot be increased beyond a safe amount by the carelessness of an operator. It may of course also be used in many other connections where it is desired to automatically or semi-automatically control the flow of an alternating current.

I have pointed out somewhat in detail the effect of a variable current in electromagnetic actuating device 60, such as that due to the acceleration of a motor upon starting. It is obvious that a variation in the strength of current in electromagnetic actuating device 70, such as a change of voltage in the line, would cause, would have a like effect. This is a valuable feature and it increases the usefulness of this invention.

What I claim is—

1. An electric circuit for alternating currents, an electromagnetic actuator in series therewith, and a second electromagnetic actuator in shunt therewith, said actuators having rotatable members mechanically connected to oppose each other.

2. An electric circuit for alternating currents, an opposition element therein, an electromagnetic actuator in series with the circuit, and a second electromagnetic actuator in shunt with the circuit, said actuators having rotatable members which are mechanically connected together and arranged to control the opposition element.

3. An electric circuit for alternating currents, an opposition element therein, an electromagnetic actuator in series with the circuit, a second electromagnetic actuator in shunt with the circuit, a retarding device for the actuators, said actuators having rotatable members which are mechanically connected to oppose each other and arranged to control the opposition element.

4. A motor, a source of alternating-current supply, and means for automatically controlling the acceleration of the motor, said means comprising an electromagnetic actuator in shunt with the motor, and a second electromagnetic actuator in series with the motor, said actuators having rotatable members, each of which members has a magnetically-equilibrated position.
- 10 5. A motor, a starting-switch therefor, a source of alternating-current supply, and means for automatically controlling the acceleration of the motor, said means comprising an electromagnetic actuator in shunt 15 with the motor, and a second electromagnetic actuator in series with the motor, said actuators having rotatable members, each of which members has a magnetically-equilibrated position.
- 20 6. A motor, an electrically-actuated reversing-switch therefor, a source of alternating-current supply, and means for automatically controlling the acceleration of the motor, said means comprising an electromagnetic actuator in shunt with the motor, and a second electromagnetic actuator in series 25 with the motor, said actuators having rotatable members, each of which members has a magnetically-equilibrated position.
- 30 7. A motor, an electrically-actuated reversing-switch therefor, a source of alternating-current supply, and means for automatically controlling the acceleration of the motor, said means comprising an electromagnetic actuator in shunt with the motor, and a second electromagnetic actuator in series 35 with the motor, said actuators having rotatable members, each of which members has a magnetically-equilibrated position, and a manually-operated switch for controlling the reversing-switch.
8. A motor, an electrically-actuated reversing-switch therefor, a source of alternating-current supply, means for automatically 45 controlling the acceleration of the motor, said means comprising an electromagnetic actuator in shunt with the motor, and a second electromagnetic actuator in series with the motor, and a manually-operated switch 50 for controlling the reversing-switch and the action of the electromagnetic actuators.
9. A motor, a source of alternating-current supply, an opposition element in the motor-circuit, means for gradually cutting said 55 position element out of the motor-circuit in proportion to the acceleration of the motor, said means comprising an electromagnetic actuator in shunt with the motor and a second electromagnetic actuator in series with the 60 motor, said actuators having rotatable members, each of which members has a magnetically-equilibrated position.
10. A motor, a source of alternating-current supply, an opposition element in the motor-circuit, means for gradually cutting said 65
- opposition element out of the motor-circuit in proportion to the acceleration of the motor, said means comprising an electromagnetic actuator in shunt with the motor, and a second electromagnetic actuator in series 70 with the motor arranged to oppose the action of said first actuator, said actuators having rotatable members, each of which members has a magnetically-equilibrated position.
11. A motor, a source of alternating-current supply, a resistance in the motor-circuit, a plurality of electromagnets arranged to short-circuit the resistance in a number of steps, and means for actuating the magnets one by one in proportion to the acceleration 80 of the motor, said means comprising an electromagnetic actuator in shunt with the motor, and a second electromagnetic actuator in series with the motor and arranged to oppose the action of said first actuator. 85
12. A motor, a source of alternating-current supply, a resistance in the motor-circuit, a plurality of electromagnets arranged to short-circuit the resistance in a number of steps, circuits for the magnets, a choking-coil in the magnet-circuits, and means for actuating the choking-coil and causing the magnets to act one by one in proportion to the acceleration of the motor, said means comprising an electromagnetic actuator in shunt 90 with the motor, and a second electromagnetic actuator in series with the motor and arranged to oppose the action of said first actuator. 95
13. A motor, a source of alternating-current supply, a resistance in the motor-circuit, a plurality of electromagnets arranged to short-circuit the resistance in a number of steps, circuits for the magnets, a choking-coil in the magnet-circuits, and means for actuating the choking-coil and causing the magnets to act one by one in proportion to the acceleration of the motor and for finally short-circuiting the entire resistance and opening the magnet-circuits, said means comprising 100 an electromagnetic actuator in shunt with the motor, and a second electromagnetic actuator in series with the motor and arranged to oppose the action of said first actuator. 105
14. A motor, a reversing-switch therefor, a source of alternating-current supply, a resistance in the motor-circuit, a plurality of electromagnets arranged to short-circuit the resistance in a number of steps, means for actuating the magnets one by one in proportion 110 to the acceleration of the motor, said means comprising an electromagnetic actuator in shunt with the motor, and a second electromagnetic actuator in series with the motor and arranged to oppose the action of said first actuator, and a retarding device for said 115 actuators. 120
15. A motor, an electrically-actuated reversing-switch therefor, a source of alternating-current supply, a resistance in the motor- 125

- 15 circuit, a plurality of electromagnets arranged to short-circuit the resistance in a number of steps, means for actuating the magnets one by one in proportion to the acceleration of the motor, said means comprising an electromagnetic actuator in shunt with the motor, and a second electromagnetic actuator in series with the motor and arranged to oppose the action of said first actuator, and a manually-operated switch for controlling the reversing-switch.
16. A motor, an electrically-actuated reversing-switch therefor, a source of alternating-current supply, a resistance in the motor-circuit, a plurality of electromagnets arranged to short-circuit the resistance in a number of steps, means for actuating the magnets one by one in proportion to the acceleration of the motor, said means comprising an electromagnetic actuator in shunt with the motor, and a second electromagnetic actuator in series with the motor and arranged to oppose the action of said first actuator, and a manually-operated switch for controlling the reversing-switch and for retarding the action of the actuating means.
17. A motor, an electrically-actuated reversing-switch therefor, a source of alternating-current supply, a resistance in the motor-circuit, a plurality of electromagnets arranged to short-circuit the resistance in a number of steps, means for actuating the magnets one by one in proportion to the acceleration of the motor, said means comprising an electromagnetic actuator in shunt with the motor, and a second electromagnetic actuator in series with the motor and arranged to oppose the action of said first actuator, a manually-operated switch for controlling the reversing-switch and for decreasing the effect of the actuating means, and an adjustable retarding device for the actuators.
18. A source of alternating-current supply, a circuit connected therewith, means for varying the current in said circuit, a magnetic actuator comprising a rotatable member of magnetic material and a winding in shunt to the circuit; and a second magnetic actuator comprising a rotatable member of magnetic material and a winding in series with the circuit, said actuators being arranged to control the current-varying means.
19. A source of alternating-current supply, a circuit connected therewith, means for varying the current in said circuit, a magnetic actuator comprising a rotatable member, a field of laminated magnetic material and a winding for the field; said winding being in shunt to the circuit; and a second magnetic actuator comprising a rotatable member, a field of laminated magnetic material and a winding for said field; said winding being in series with the circuit, said rotatable members being arranged to control the current-varying means.

20. A source of alternating-current supply, a circuit connected therewith, means for varying the current in said circuit, a magnetic actuator comprising a rotatable member of laminated magnetic material, a frame of laminated magnetic material and a winding for the frame; said winding being in shunt to the circuit; and a second magnetic actuator comprising a rotatable member of laminated magnetic material, a frame of laminated magnetic material and a winding for the frame; said winding being in series with the circuit; said rotatable members being mechanically geared together and arranged to control the current-varying means.
21. A source of alternating-current supply, a circuit connected therewith, means for varying the current in said circuit, a magnetic actuator comprising a rotatable member of laminated magnetic material, a field of laminated magnetic material and a winding for the field; said winding being in shunt to the motor; a second magnetic actuator comprising a rotatable member of laminated magnetic material, a field of laminated magnetic material and a winding for said field; said winding being in series with the circuit; said rotatable members being mechanically geared together and to a lever which is arranged to control the current-varying means, and an adjustable weight on said lever.
22. A source of alternating-current supply, a circuit connected therewith, an inductive means for varying the current in said circuit, a magnetic actuator comprising a rotatable member and a winding in shunt to the circuit; and a second magnetic actuator comprising a rotatable member and a winding in series with the circuit, said actuators being arranged to mechanically control the inductive-current-varying means.
23. A source of alternating-current supply, a circuit connected therewith, an opposition element in said circuit, an electroresponsive device for controlling the opposition element, inductive means for controlling the electroresponsive device, a magnetic actuator comprising a rotatable member of magnetic material and a winding in shunt to the circuit, and a second magnetic actuator comprising a rotatable member of magnetic material and a winding in series with the circuit, said actuators being arranged to control the inductive-current-varying means.
24. A source of alternating-current supply, a circuit connected therewith, means for varying the current in said circuit, a magnetic actuator comprising a rotatable member of laminated magnetic material, a frame of laminated magnetic material and a winding for the frame; said winding being in shunt to the circuit, and a second magnetic actuator comprising a rotatable member of laminated magnetic material, a frame of laminated magnetic material and a winding for

- the frame; said winding being in series with the circuit, and means for electrically retarding the action of the actuators.
25. A source of alternating-current supply, a circuit connected therewith, means for varying the current in said circuit, a magnetic actuator comprising a rotatable member of laminated magnetic material, a frame of laminated magnetic material and a winding for the frame; said winding being in shunt to the circuit, and a second magnetic actuator comprising a rotatable member of laminated magnetic material, a frame of laminated magnetic material and a winding for the frame; said winding being in series with the circuit, and means for electrically retarding the action of the actuators and additional means for mechanically retarding the action of the actuators.
- 20 26. A source of alternating-current supply, a circuit connected therewith, means for varying the current in said circuit, a magnetic actuator comprising a rotatable member of laminated magnetic material, a frame of laminated magnetic material and a winding for the frame; said winding being in shunt to the circuit, and a second magnetic actuator comprising a rotatable member of laminated magnetic material, a frame of laminated magnetic material and a winding for the frame; said winding being in series with the circuit, and manually-operated means for adjustably decreasing the current in said shunt-winding, and additional means for retarding the movement of the actuators.
- 25 27. A motor, a source of alternating-current supply therefor, means for varying the current in the motor, a magnetic actuator comprising a rotatable member of laminated magnetic material, a frame of laminated magnetic material and a winding for the frame; said winding being in shunt to the motor; and a second magnetic actuator comprising a rotatable member of laminated magnetic material, a frame of laminated magnetic material and a winding for the frame; said winding being in series with the motor; said rotatable members being mechanically geared together and arranged to control the current-varying means.
- 30 28. A motor, a source of alternating-current supply therefor, an opposition element in the motor-circuit, an electroresponsive device for controlling the opposition element, inductive means for controlling the electroresponsive device, a magnetic actuator comprising a rotatable member of magnetic material and a winding in shunt to the motor, and a second magnetic actuator comprising a rotatable member of magnetic material and a winding in series with the motor, said actuators being arranged to control the inductive-current-varying means.
- 35 29. A motor, a source of alternating-current supply therefor, a resistance in the motor-circuit, an electroresponsive device arranged to control the resistance, inductive means arranged to control the electroresponsive device, a magnetic actuator comprising a rotatable member of magnetic material, and a winding in shunt to the motor; a second magnetic actuator comprising a rotatable member and a winding in series with the motor, said rotating members being mechanically connected together and to the inductive means, and arranged to cause said inductive means to control the electroresponsive device to remove the resistance from the motor-circuit.
- 40 30. A motor, a source of alternating-current supply therefor, a resistance in the motor-circuit, an electroresponsive device comprising a plurality of magnets arranged to control the resistance, inductive means arranged to control the electroresponsive device, a magnetic actuator comprising a rotatable member of magnetic material, and a winding in shunt to the motor; a second magnetic actuator comprising a rotatable member and a winding in series with the motor, said rotating members being mechanically connected together and to the inductive means and arranged to cause said inductive means to control the magnets to cut the resistance out of the motor-circuit step by step.
- 45 31. A motor, a starting-switch therefor, a source of alternating-current supply, means for automatically controlling the acceleration of the motor, said means comprising an electromagnetic actuator having a rotatable member and a winding in shunt with the motor, a second electromagnetic actuator having a rotatable member and a winding in series with the motor and means combined with the starting-switch for controlling said actuator-windings.
- 50 32. A motor, an electrically-actuated reversing-switch therefor, a source of alternating-current supply, means for automatically controlling the acceleration of the motor, said means comprising an electromagnetic actuator having a rotatable member and a winding in shunt with the motor, and a second electromagnetic actuator having a rotatable member and a winding in series with the motor-circuits for said windings, means combined with the reversing-switch for closing and opening the circuits for the actuator-windings, and a manually-operated switch arranged to control the reversing-switch and to control and regulate the action of the electromagnetic actuators.
- 55 33. A multiphase alternating-current motor, a source of multiphase alternating-current supply and means for automatically controlling the acceleration of the motor, said means comprising a magnetic actuator in shunt with the motor and a second mag-

netic actuator in series with the motor, said actuators being arranged to be energized by a single-phase current.

34. A multiphase alternating-current motor, a source of multiphase alternating-current supply therefor, an electrically-actuated reversing-switch for the motor and means for automatically controlling the acceleration of the motor, said means comprising an electromagnetic actuator in shunt with the motor, and a second magnetic actuator in series with the motor, and a manually-operated switch for controlling the reversing-switch and the action of the electromagnetic actuators, said reversing-switch and actuators being arranged to be energized by a single-phase current.

35. A multiphase alternating-current motor, a source of multiphase alternating-current supply therefor, an electrically-actuated reversing-switch for the motor, an electroresponsive device comprising a plurality of magnets arranged to control the resistance, inductive means arranged to control the electroresponsive device, a magnetic actuator comprising a rotatable member of magnetic material and a winding in shunt with the motor; a second magnetic actuator comprising a rotatable member and a winding in series with the motor, said rotatable members being mechanically connected together and to the inductive means, and arranged to cut the resistance out of the motor-circuit step by step, and a manually-operated switch arranged to control the reversing-switch and to control and regulate the action of the electromagnetic actuators, said reversing-switch, magnets, inductive means and actuators being arranged to be energized by a single-phase current.

36. A motor, a source of alternating-current supply therefor, an opposition element in the motor-circuit, a plurality of electromagnets, inductive means arranged to control the magnets and an electromagnetic actuator having a rotatable member, said member being arranged to mechanically control the inductive means.

37. A motor, a source of alternating-current supply therefor, an opposition element in the motor-circuit, a plurality of electromagnets, inductive means arranged to control the magnets and an electromagnetic actuator having a rotatable member, said member being arranged to mechanically control the inductive means to cause the magnets to be actuated step by step in proportion to the speed of the motor.

38. A motor, a source of alternating-current supply therefor, an opposition element in the motor-circuit, a plurality of electromagnets, inductive means arranged to control the magnets, an electromagnetic actuator having a rotatable member, said member

being arranged to mechanically control the inductive means, and means for electrically retarding the action of the actuator.

39. A motor, a source of alternating-current supply therefor, an opposition element in the motor-circuit, electromagnetic actuating means controlled by the total amount of current flowing through the motor and by the amount of voltage in the source of supply, and arranged to control the opposition element.

40. A motor, a source of alternating-current supply therefor, an opposition element in the motor-circuit, an electroresponsive device arranged to control the opposition element, circuits for said electroresponsive device, inductive means in the said circuits and an electromagnetic actuator arranged to control the inductive means.

41. A motor, a source of alternating-current supply therefor, a resistance in the motor-circuit, a series of electromagnets each arranged to short-circuit a part of said resistance, an inductive device arranged to control the magnets, a magnetic actuating device dependent upon the motor-current and the voltage of the supply, mechanically connected to the inductive device and arranged to move the inductive device to cause the magnets to be actuated step by step and to finally effect the short-circuiting of the entire resistance.

42. A motor, a source of alternating-current supply, a resistance in the motor-circuit, a series of electromagnets each arranged to short-circuit a portion of the resistance, an inductive device to control the magnets, electromagnetic actuating means dependent upon the current in the motor and the voltage of the supply, mechanically connected to the inductive device and means mechanically connected to the actuating means for short-circuiting the final portion of the resistance and cutting out the magnets and the inductive device.

43. A motor, a source of alternating-current supply therefor, an opposition element in the motor-circuit, an electromagnetic actuator arranged to control said opposition element, said actuator having a circuit in series with the motor and another circuit in shunt with the motor; and manually-operated means for controlling the current in the shunt-circuit.

44. An alternating-current motor, a circuit therefor, an opposition element in the motor-circuit, an electroresponsive device arranged to control said opposition element, inductive means arranged to control the electroresponsive device, and an electromagnetic actuator arranged to control the inductive means.

45. An alternating-current motor, a circuit therefor, an opposition element in the

motor-circuit, an electroresponsive device arranged to control said opposition element, inductive means arranged to control the electroresponsive device, and an electromagnetic 5 actuator arranged to control the inductive means, said electromagnetic actuator being governed by the current in the motor-circuit.

46. A source of alternating-current supply, an alternating-current motor, a circuit therefor, an opposition element in the motor-circuit, an electroresponsive device arranged to control said opposition element, inductive means arranged to control the electroresponsive device, and an electromagnetic actuator 15 arranged to control the inductive means, said electromagnetic actuator being governed by the current in the motor-circuit and by the potential of the source of supply.

47. An alternating-current motor, a circuit therefor, an opposition element in the motor-circuit, an electroresponsive device arranged to cut the opposition element out of the motor-circuit step by step, circuits for the electroresponsive device, inductive means 25 arranged to control the current in said circuit, and an electromagnetic actuator arranged to control the inductive means.

48. An alternating-current motor, a circuit therefor, an opposition element in the motor-circuit, an electroresponsive device arranged to cut the opposition element out of the motor-circuit step by step, circuits for the electroresponsive device, inductive means 30 arranged to control the current in said circuits, an electromagnetic actuator arranged to control the inductive means, and retarding means for the actuator.

49. An alternating-current motor, a circuit therefor, an opposition element in the motor-circuit, an electroresponsive device arranged to cut the opposition element out of the motor-circuit step by step, circuits for the electroresponsive device, inductive means 40 arranged to control the current in said circuits, an electromagnetic actuator arranged to control the inductive means, a mechanical retarding device for the actuator, and an electrical retarding device for the actuator.

50. A controlling device, comprising two 45 rotatable members constructed of laminated magnetic material, said rotatable members being mechanically connected together and

each of said members having a magnetically-equilibrated position.

51. A controlling device, comprising two 55 rotatable members constructed of laminated magnetic material, said rotatable members being mechanically connected together and each of said members having a magnetically-equilibrated position, and means for magnetizing said members.

52. A controlling device comprising two 60 rotatable members constructed of laminated magnetic material, said rotatable members being mechanically connected together, a 65 source of alternating-current supply arranged to magnetize said members, each of said members having a magnetically-equilibrated position; and means for controlling said source of supply. 70

53. An alternating-current motor, means for controlling said motor, said means comprising two rotatable members constructed of laminated magnetic material, and said rotatable members being mechanically connected together, each of said members having a magnetically-equilibrated position. 75

54. An alternating-current motor, a circuit therefor, an opposition element in the motor-circuit, means for controlling said opposition element, said means comprising two 80 rotatable members constructed of laminated magnetic material, and said rotatable members being mechanically connected together, each of said members having a magnetically-equilibrated position. 85

55. An alternating-current motor, a circuit therefor, an opposition element in the motor-circuit, means for controlling said opposition element in proportion to the speed 90 of the motor, said controlling means comprising two rotatable members constructed of laminated magnetic material, and said rotatable members being mechanically connected together, each of said members having a magnetically-equilibrated position. 95

In testimony whereof I have signed my name to this specification in the presence of two subscribing witnesses.

DAVID LARSON.
